Application November 15, 1946, Serial No. 134,810

Term of patent 14 years

(Cl. D52—3)

To all whom it may concern:

Be it known, that we, William J. During and John J. Punke, citizens of the United States, residing at Fayetteville, in the county of Onondaga and State of New York, and at Dewitt, in the county of Onondaga and State of New York, respectively, have invented a new, original, and ornamental Design for a Drink Vending Machine, of which the following is a specification, reference being had to the accompanying drawing, forming part thereof.

In the drawing:

Figure 1 is a front elevational view of a drink vending machine showing our new design.

Figure 2 is a side elevational view.

We claim:
The ornamental design for a drink vending machine, substantially as shown.

WILLIAM J. DURING.
JOHN J. PUNKE.
